DESIGN FOR A BED LAMP

Jack Galter, Chicago, Ill.

Application January 13, 1941, Serial No. 98,010

Term of patent 7 years

To all whom it may concern:

Be it known that I, Jack Galter, a citizen of the United States of America, residing at 711 West Lake Street, Chicago, Illinois, have invented a new, original, and ornamental Design for a Bed Lamp, of which the following is a specification, reference being had to the accompanying drawing, forming a part thereof.

Fig. 1 is a perspective view; Fig. 2 is a front elevational view; Fig. 3 is a bottom plan view; and Fig. 4 is an end elevational view of a bed lamp embodying my new design.

I claim:

The ornamental design for a bed lamp, substantially as shown.

JACK GALTER.
